SMOKING PIPE

Arthur R. Wood, New York, N. Y.

Application February 21, 1948, Serial No. 10,079

6 Claims. (Cl. 131—202)

1

This invention relates to smoking pipes and has for an object to provide a pipe having improved smoking characteristics.

Another object is to provide a pipe of novel and improved construction.

Another object is to provide a pipe which is capable of completely burning its entire charge of tobacco without developing excessive heat or caking.

Another object is to provide a pipe having a filter chamber through which the dry smoke passes and which contains a selected flavoring material.

Various other objects and advantages will be apparent as the nature of the invention is more fully disclosed.

In accordance with the present invention, the pipe stem is provided with upper and lower parallel channels extending between the pipe bowl and the mouthpiece. The upper channel contains smoke filtering material and the lower channel contains an absorbent material. The pipe bowl and mouthpiece both drain into the lower channel so that nicotine and tars from the bowl and saliva from the mouthpiece are drained into the two ends of the absorbent material and thus removed from the smoke path. The upper channel also drains directly into the absorbent material so that all condensate is immediately removed from the upper channel as soon as it forms therein.

The upper channel may contain a plurality of perforated chalk discs and a filler of cotton or other filter material which may carry a flavoring material such as honey.

Although the novel features which are characteristic of this invention are pointed out more in detail in the claims, the nature of the invention will be better understood by referring to the following description, taken in connection with the accompanying drawings in which a specific embodiment thereof has been set forth for purposes of illustration.

In the drawings:

Fig. 1 is a top plan view of a pipe embodying the invention;

Fig. 2 is a vertical longitudinal section taken on the line 2—2 of Fig. 1;

Fig. 3 is a transverse section taken on the line 3—3 of Fig. 2;

Figs. 4, 5 and 6 are transverse sections taken on the lines 4—4, 5—5 and 6—6, respectively, of Fig. 2;

Fig. 7 is a perspective view of the cartridge case; and

Fig. 8 is a perspective view of a chalk disc.

2

Referring to the embodiment shown in Figs. 1—8, the pipe comprises a bowl 15 of the usual shape and material, having a base 16 terminating in a flange 17 forming a trap chamber 18. A plurality of passages 19 extend between the bowl 15 and the chamber 18. These passages are distributed across the base 16 to provide a more nearly uniform draft than would be the case with a single passage and to thereby cause the tobacco to burn evenly across the bowl.

A connector 22, made of cork, rubber or other soft material, is formed with a transverse wall and an annular flange 23 seated within the chamber 18. A plug 24 of a solid adsorbent material such as chalk is disposed in the end of the flange 23 and is provided with a plurality of passages 25. A chamber 26 is formed in the connector 22 beyond the plug 24 which may be filled with a suitable adsorbent or filtering material such as a combination of mineral wool and cotton.

A cartridge 30 comprising a peripheral wall 31 and a dividing wall 32 extends from the connector 22 which is recessed to receive one end of the wall 32. The walls 31 and 32 may be made of a suitable material such as heavy paper. The wall 32 divides the cartridge 30 into an upper chamber 33 and a lower chamber 34. Passages 35 and 36 in the connector 22 extend from the top and bottom, respectively, of the chamber 26 to the chambers 33 and 34, respectively. The wall 32 is formed with a plurality of perforations 37 which drain the condensate from the chamber 33 into the lower chamber 34.

The upper chamber 33 contains a section of filter material 38 such as cotton which may be impregnated with a flavoring material such as honey. Alternatively dried fruits or vegetables or other flavoring material may be used.

At each end, the chamber 33 carries discs 39 of a solid adsorbent material such as chalk (Fig. 8) having transverse passages 40 therein and recesses 41 in at least one face to provide smoke chambers between successive discs 39.

The lower chamber is filled with a suitable adsorbent material 43 such as cotton which may have a wick at each end extending through the passages 36 and 46.

The other end of the peripheral wall 31 of the cartridge 30 is secured over the reduced end of a mouthpiece 47 containing a connector 44 which may be made of cork or rubber. The connector 44 is recessed to receive the end of the wall 32 and has passages 45 and 46 extending from the chambers 33 and 34, respectively.

The mouthpiece or bit 47 has the usual axial

3

passage 48. A small saliva trap 49 is formed in the mouthpiece 47 between the passage 48 and the end of the connector 44. The saliva trap 49 is shown as an oval shaped chamber extending both above and below the passage 48 to pick up any condensation as well as moisture and drain the same to the passage 46.

The mouthpiece 47 and bowl 15 are additionally secured together by a metal sleeve 50. The pipe may be disassembled by removing the bowl 15 and mouthpiece 47 from the sleeve 50, pushing the cartridge 30, with connectors 22 and 44 attached, out of the sleeve, and then removing the connectors from the cartridge to expose the chambers 33 and 34.

It is contemplated that when the absorbent material 43 in the chamber 34 becomes saturated, the entire cartridge 30 will be discarded and replaced by a new cartridge. However the absorbent material 43 may be renewed in the chamber 34 if desired.

In the operation of this pipe the nicotine and tars are trapped in the chamber 26 and are absorbed by the material 43 in the chamber 34, following the wick through the passage 36. The smoke passes through the plug 24, chamber 26 and passage 35 into the upper chamber 33 of the cartridge 30 where it is purified by the chalk discs 39 and passes through the filter material 38 and the flavoring material therein.

Any condensate in the chamber 33 passes through the perforations 37 to the absorbent material in the chamber 34. The dry smoke then flows through the passage 45 to the mouthpiece 47. Any saliva from the mouthpiece is separated in the chamber 49 and flows through the passage 46 to the chamber 34 where it is absorbed by the absorbent material 43. The thin wick of the absorbent material may extend from the chamber 34 through the passage 46 to pick up and carry the saliva or moisture to the lower chamber. Hence the smoke remains dry at all times and the usual irritation is avoided. Also by removing the tar and moisture from the bowl the tobacco is kept dry and burns more evenly without making a deposit or hard cake in the bowl.

The perforated chalk plug 24 breaks up the smoke stream into a plurality of fine threads or streams, retards the heat transfer to the pipe stem, and assists in filtering the tar to thereby assure a cool smoke.

Although a certain specific embodiment has been shown for purposes of illustration, it is to be understood that the invention is capable of various uses and that changes and modifications may be made therein as will be readily apparent to a person skilled in the art.

What is claimed is:

1. A smoking pipe comprising a bowl having a base including an annular flange forming a trap chamber, passages connecting said bowl to said chamber, a replaceable stem adapted to be attached to said flange, said stem having a horizontal wall forming separate upper and lower passages along said stem, a transverse wall partially closing the bowl end of said upper and lower passages, an annular connecting flange extending axially from said transverse wall and fitting in said first flange to secure said stem to said bowl, said transverse wall forming a partial closure for said trap chamber, a smoke passage through said transverse wall from the upper part of said trap chamber to said upper passage, a

4

drain passage through said transverse wall from the lower part of said trap chamber to said lower passage, and a mouthpiece removably secured to said stem and having separate passages to said upper and lower passages.

2. In a smoking pipe as set forth in claim 1, filtering material in said trap chamber and in said upper passage and absorbent material in said lower passage.

3. In a smoking pipe as set forth in claim 1, filtering material in said trap chamber and in said upper passage and absorbent material in said lower passage, said absorbent material extending as a wick through said drain passage in said transverse wall.

4. In a smoking pipe as set forth in claim 1, filtering material in said trap chamber and in said upper passage and absorbent material in said lower passage, said absorbent material extending as a wick through said drain passage in said transverse wall and through the lower passage of said mouthpiece.

5. A stem for attachment to the bowl and mouthpiece of a smoking pipe, comprising a peripheral wall and a horizontal wall therein forming separate upper and lower passages along said stem, a transverse wall partially closing the forward end of said upper and lower passages, an annular connecting flange extending axially from said transverse wall for attachment to the pipe bowl and forming with said transverse wall a trap chamber, a smoke passage through said transverse wall from the upper part of said trap chamber to said upper passage, and a drain passage through said transverse wall from the lower part of said trap chamber to said lower passage.

6. A stem for attachment to the bowl and mouthpiece of a smoking pipe, comprising a peripheral wall and a horizontal wall therein forming separate upper and lower passages along said stem, a transverse wall partially closing the forward end of said upper and lower passages, an annular connecting flange extending axially from said transverse wall for attachment to the pipe bowl and forming with said transverse wall a trap chamber, a smoke passage through said transverse wall from the upper part of said trap chamber to said upper passage, a drain passage through said transverse wall from the lower part of said trap chamber to said lower passage, filtering material in said upper passage and in said trap chamber and absorbent material in said lower passage.
